SUCTION BRUSH FOR CLEANING VENETIAN BLINDS

Joseph P. Zaidan, Philadelphia, Pa.

Application September 22, 1954, Serial No. 32,387

Term of patent 14 years

(Cl. D9—2)

Fig. 1.

Fig. 2.

Fig. 3.

Fig. 4.

Figure 1 is a top plan view of a suction brush for cleaning venetian blinds showing my new design.

Figure 2 is a side elevational view.

Figure 3 is an end view.

Figure 4 is an end view opposite to that of Figure 3.

I claim:

The ornamental design of a suction brush for cleaning venetian blinds, as shown.
